UNITED STATES PATENT OFFICE

115,502

DESIGN FOR A TRANSPARENT MOTHPROOF GARMENT CONTAINER

William R. Kohl, Glen View, Ill.

Application November 3, 1938, Serial No. 80,970

Term of patent 14 years

To all whom it may concern:

Be it known that I, William R. Kohl, a citizen of the United States of America, a resident at Glen View, in the county of Cook and State of Illinois, have invented a new, original, and ornamental Design for a Transparent Mothproof Garment Container, of which the following is a specification, reference being had to the accompanying drawing, forming part thereof.

Fig. 1 is a side elevational view of a transparent mothproof garment container showing my new design;

Fig. 2 is a top plan view; and
Fig. 3 is an end elevational view.

I claim:

The ornamental design for a transparent mothproof garment container, as shown.

WILLIAM R. KOHL.
